SOLVENT EXTRACTION OF MINERAL
LUBRICATING OILSClifford C. Buchler and Sterling H. Diggs, Casper,
Wyo., assignors to Standard Oil Company, Chi-
cago, Ill., a corporation of Indiana

Application February 17, 1936, Serial No. 64,202

8 Claims. (Cl. 196—13)

This invention relates to a process of refining mineral oils and specifically petroleum lubricating oils of the type employed in the lubrication of internal combustion engines and commonly known as motor oils. The invention further relates to a process of extracting such oils with a specific solvent, namely; beta beta' dichlor diethyl ether, hereinafter referred to as "chlor-ether". The use of this solvent for the extraction of mineral lubricating oils has been previously described in United States Patent No. 2,003,238, entitled "Process of separating mineral oils", by H. T. Bennett, filed June 23, 1933.

More particularly, the present invention relates to an improvement in the use of beta beta' dichlor diethyl ether in lubricating oil extraction processes, wherein undesirable naphthenic constituents are removed from the paraffinic component of the oil. One object of the invention is to facilitate the use of said chlor-ether solvent in the extraction of wax-containing lubricating oil stocks. Another object of the invention is to increase the selective solvent action of said solvent by the addition of minor amounts of certain modifying agents.

In the extraction of Mid-Continent and Salt Creek lubricating distillates such as motor oil distillates falling within the viscosity range of 20-60 S. A. E. number, difficulty has frequently been encountered with separation of wax in the extraction process. Where the distillate contains over 5% of paraffin wax and frequently as much as 10 or 15% thereof, the wax will usually crystallize in the form of a thick mush or magma at ordinary temperatures and even at temperatures in the range of 100-125° F. This is especially true of the heavier distillates which contain higher melting waxes.

When extracting such wax-containing oils with beta beta' di-chlor diethyl ether it is usually necessary to maintain the temperature of the oil undergoing extraction below 110° F. in order to obtain a satisfactory yield of refined lubricating oil, or raffinate, having the desired viscosity index. It is, accordingly, not feasible to carry out the extraction process at a temperature sufficiently high to maintain the wax in liquid form.

We have now discovered that certain substances may be added to the chlor-ether in relatively small amounts, usually not exceeding 20% and ordinarily from 2 to 10%, which will enable the extraction operation to be conducted at higher temperatures where the paraffin wax contained in the oil will remain in liquid condition and at the same time a satisfactory separation of oil

from solvent can be obtained without materially sacrificing either yield or viscosity index. The substances having this desirable property belong to the class of organic alkyl hydroxy compounds, more particularly polyhydroxy alcohols such as 5 the glycols. Examples of such compounds are ethylene glycol, propylene glycol, butylene glycol, di-ethylene glycol, tri-ethylene glycol and tri-methylene glycol; alcohols such as ethyl, propyl and butyl alcohols may be used but are not as 10 satisfactory as the polyhydroxy alcohols above mentioned and also usually cause difficulty in handling due to their relatively low boiling points. The high boiling points of the polyhydroxy alcohols make it possible to recover these materials 15 along with the chlor-ether; losses by evaporation are substantially nil.

The solubility of ethylene glycol in anhydrous beta beta' dichlor di-ethyl ether is shown in the following table:

Temperature	Percent ethylene glycol in anhydrous chloro- glycol mixture
110	Trace
115	2
120	4
130	5.2
150	5.5

When using this modifying agent, the amount to be added will preferably not exceed that which will dissolve at the minimum temperature of extraction, and in any case it will not exceed that which will dissolve at the highest temperature 35 of mixing solvent and oil.

The effect of hydroxy alkyl compounds in increasing the miscibility temperature of oils and chlor-ether is shown by an example in which a light oil having a specific gravity of .8338 (60° F.) 40 was mixed with chlor-ether at 75° F. at which temperature it was completely miscible with the solvent. On the addition of one volume of 95% ethyl alcohol to the chlor-ether a separation of the oil was obtained without lowering the temperature.

As an example of the effect of glycol in improving the extraction of a mineral lubricating oil with chlor-ether, a heavy lubricating distillate of S. A. E. 60 viscosity range was extracted with 50 solvent in the ratio of two parts of solvent to one part of oil, by volume, in a single batch application. One portion of oil was extracted with chlor-ether at a temperature of 80° F., giving a yield of 83% of raffinate having a viscosity index of 84.5. 55

Another portion of oil was extracted with chlor-ether saturated with ethylene glycol at a temperature of 87° F., giving a yield of 83% of raffinate having a viscosity index of 86. This illustrates the effect of the glycol in permitting the extraction to be carried out at a higher temperature, giving substantially the same yield and actually improving the viscosity index.

The drawing which forms a part of this specification illustrates graphically the effect of certain modifying agents in the chlor-ether extraction process.

The effect of glycols in increasing the yield or raffinate at higher temperatures is well illustrated by the graph shown in Fig. 1 where the yield of raffinate in percent by weight is plotted against the temperature of extraction in degrees Fahrenheit. The curves in this graph were obtained by extracting dewaxed lubricating distillate having a viscosity in the range of S. A. E. 60, the wax having been removed in order to avoid difficulties in obtaining extraction at the lower temperatures. The oil was extracted with two volumes of solvent in a single application. The chart shows that for a given yield of raffinate there is a decided increase in the temperature of extraction; for example, in order to obtain a yield of 76% under these conditions it is necessary to operate at a temperature of 108° F. with pure chlor-ether. The addition of 4% propylene glycol permits obtaining the same yield at a temperature of about 120° F. and the use of a saturated solution of ethylene glycol in the di-chlor ether increases the permissible extraction temperature to about 123° F.

Fig. 2 shows in a graphical way the effect of additions of glycols to chlor-ether with respect to the temperature of complete miscibility of the solvent with a heavy mineral lubricating oil. The data given in this graph were obtained on the same oil as used in determining the data for Fig. 1, i. e., a dewaxed distillate from Salt Creek crude having a viscosity in the range of 60 S. A. E. The ratio of solvent to oil was varied as indicated in the chart and glycols were added to the solvent in an amount of 4% by volume. From these results it will be seen that, employing a solvent ratio of 2 to 1, the temperature of complete miscibility is raised from about 152° F. with pure chlor-ether to 180° F. with chlor-ether saturated with ethylene glycol. Propylene glycol and di-ethylene glycol also raised the miscibility temperature very considerably when used in this amount.

To illustrate the advantage of this invention in overcoming difficulty with wax separation, the extraction of a lubricating distillate from Salt Creek crude (used in making S. A. E. 50 grade motor oil) may be referred to. Such an oil becomes completely miscible with chlor-ether in all proportions at about 139° F. When the oil is cooled to cause an extract layer to separate it is found that solid wax begins to separate at about 128° F. In the extraction of this oil therefore it is usually necessary to maintain the operating temperature within a carefully controlled range of temperature if difficulties from wax sep-

aration are to be avoided. When extracting in countercurrent towers the separation of wax is most objectionable and a temperature range of only 8° F. must be maintained with an oil such as above. The addition of the hydroxy alkyl compounds even in small proportions greatly alleviates these rigid operating requirements.

Having thus described our invention, what we claim is:

1. In the process of extracting undesirable naphthenic constituents from wax-containing mineral hydrocarbon lubricating oils wherein the oil is intimately contacted with beta beta' dichlor diethyl ether and the undesirable naphthenic constituents are removed as an extract in solution in said ether, the improvement comprising incorporating in said beta beta' dichlor diethyl ether from 2 to 20% of an alkylene glycol and conducting the extraction at a temperature above the solidifying point of the wax-containing oil.

2. The process of claim 1 wherein the alkylene glycol is ethylene glycol.

3. The process of claim 1 wherein said alkylene glycol is diethylene glycol.

4. In the process of extracting undesirable naphthenic constituents from wax-containing mineral lubricating oils wherein the oil is intimately contacted with beta beta' dichlor diethyl ether and the undesirable constituents are removed as an extract in solution in said ether, the improvement comprising conducting the extraction at a temperature above the solidifying point of the oil and modifying the solvent action of said beta beta' dichlor diethyl ether by incorporating therein from 2 to 7% of ethylene glycol before the contacting step.

5. In the process of extracting mineral hydrocarbon lubricating oils containing paraffin wax and undesirable naphthenic hydrocarbons with beta beta' dichlor diethyl ether wherein the oil is intimately contacted with the ether and the oil and ether, are separated into two phases in which the heavier ether phase contains dissolved undesirable naphthenic hydrocarbon constituents of the oil, the improvement comprising avoiding difficulties resulting from the separation of solid paraffin wax as a third phase in the process by adding between 2% and 20% of a dihydroxy alkyl compound to the beta beta' dichlor diethyl ether whereby the miscibility temperature of said ether and said lubricating oil is raised substantially above the melting point of said waxy oil and conducting the extraction at a temperature between the melting point of said waxy oil and the said raised miscibility temperature, whereby said wax is prevented from crystallizing as a separate phase from said mixture during the extraction operation.

6. The process of claim 5 wherein the dihydroxy alkyl compound is ethylene glycol.

7. The process of claim 5 wherein the dihydroxy alkyl compound is butylene glycol.

8. The process of claim 5 wherein the dihydroxy alkyl compound is diethylene glycol.
